CLAIM

The ornamental design for a combination floor lamp and compact disc holder, as shown and described.

DESCRIPTION

FIG. 1 is a front-elevational view of a combination floor lamp and compact disc holder, showing my new design thereof;

FIG. 2 is a rear-elevational view thereof;

FIG. 3 is a right side-elevational view thereof;

FIG. 4 is a perspective of the front and left side thereof;

FIG. 5 is a top plan view thereof; and,

FIG. 6 is a bottom plan view thereof.
